SLUG CASTING MACHINE

Herman T. Sundstrom and Clarence A. Stopple,
Houston, Tex., assignors to Mergenthaler Linotype Company, a corporation of New York

Application February 4, 1939, Serial No. 254,585

16 Claims. (CL 199—50)

This invention relates to slug casting machines of the general organization represented in U. S. Letters Patent to O. Mergenthaler, No. 436,532 wherein circulating matrices and interposed spacers are assembled in line and then presented against the front face of a slotted mold where they are expanded or justified between a pair of confining jaws, the mold filled with molten metal to form a type bar or slug against the 5 matrices which produce the type characters thereon, and, finally, after the casting operation, elevated from the jaws and distributed.

In practice, it is necessary to change frequently the length of the slugs produced, according to the 15 width or measure of the page or column to be printed. In consequence, the mold slot in which the slugs are cast is made variable in length, and one of the confining jaws is made adjustable to correspond so that lines of one length or another 20 may be used at will. The adjustable jaw is carried by a sustaining member which is adapted and arranged to be adjusted in ems or half-ems along a toothed rod mounted in bearings secured to the vise frame of the machine. At a point between the bearings, the rod is provided with a fixed collar which abuts against a vertical reciprocating wedge, the latter being supported facewise by an intermediate anti-wear shoe which banks against the inner end of a bushing 25 clamped in the left-hand bearing. In rising, the wedge forces the rod and the jaw coupled thereto slightly to the right against the action of a spring so as to position the jaw exactly to measure prior to the expansion or justification of the line between the jaws, and, in descending, the wedge allows the spring to retract the rod a similar distance so that the line may be lifted readily from the jaws for distribution after the casting operation.

40 The left-hand bearing is split, and the bushing against the inner end of which the anti-wear shoe banks is threaded therein and maintained in fixed position by means of a clamping screw. Ordinarily, therefore, the jaw is adjustable only 45 to standard slug measures, namely, ems or half-ems, as permitted by the spacing of the teeth on the toothed rod. Occasionally, however, bastard slug measures are desired which require an auxiliary adjustment of the left-hand jaw in fractions of less than a half-em, and such adjustments are now made by loosening the clamping 50 screw and turning the bushing to adjust the inner end thereof the slight extent required.

Aside from the fact that considerable time and 55 effort are required to thus make an auxiliary

adjustment of the left-hand jaw, it has been found in practice that after the bushing has been turned the adjustment so made is frequently disturbed when the clamping screw is retightened.

The present invention is intended to enable the operator to make an adjustment of the left-hand jaw in fractions of less than a half-em without the necessity of loosening and thereafter retightening the clamping screw in the left-hand bearing. To this end, the usual bushing in the left-hand bearing is replaced with one having an auxiliary bushing adjustably mounted therein. In assembly, the main bushing is clamped in the left-hand bearing in the usual way, with its inner end in position to permit the anti-wear shoe to bank against it as the wedge rises prior to justification, and the auxiliary bushing stands clear of the anti-wear shoe so as to permit the slugs to be cast to standard measure in ems or half-ems. When, however, it is desired to cast slugs to bastard measures or in fractions of less than a half-em, the auxiliary bushing is adjusted until the inner end thereof protrudes beyond the inner end of the fixed main bushing the required 20 amount and so, through the anti-wear shoe and the wedge, sets the toothed rod and the jaw to the right a like distance.

In the accompanying drawings, the invention has been shown merely in preferred forms and 30 by way of example, but obviously many changes and variations may be made therein and in its mode of application which will still be comprised within its spirit. It should, therefore, be understood that the invention is not limited to any 35 specific form or embodiment except insofar as such limitations are specified in the claims.

Fig. 11 is a front view of the parts shown in Fig. 10;

Fig. 12 is a vertical section taken along the line 12—12 in Fig. 10; and

Fig. 13 is a face view of the locking plate employed in this third embodiment of the invention.

A composed line of matrices and spacers when presented at the casting level is confined endwise between a pair of vise jaws 10, 11, which are carried respectively by angular blocks 12, 13, mounted in a stationary portion 14 of the so-called vise frame. The left-hand block 12 is formed with bearing portions 15, 16, slidably mounted in suitable guideways so that the left-hand jaw 10 may be moved toward and from the fixed opposing right-hand jaw 11 to vary the distance therebetween according to the length of the composed lines employed. The movement of the left-hand jaw 10 toward and away from the fixed right-hand jaw 11 is effected by means of a sustaining member 17 mounted in a carriage 23 arranged at the left of the supporting block 12 and which, like the bearing portions of the block, is mounted in guideways of the vise frame. The sustaining member 17 is adapted and arranged to be carried into and out of operative engagement with the toothed portion 19 of a rod 18 mounted in horizontal bearings 20, 21, spaced apart and projecting rearwardly from a bracket 22 secured to the vise frame, its engagement with the rod 18 being broken to permit the carriage 23 to be shifted horizontally for setting the jaw 10 in a desired position with respect to the fixed right-hand jaw 11, and its engagement with the rod 18 being made so as to sustain the jaw 10 in desired position. As usual, in such machines, the spacing of the teeth on the rod 18 and the cooperating teeth on the sustaining member 17 is such that the position of the left-hand jaw 10 may be adjusted with respect to the right-hand jaw 11 in ems or half-ems. The operation of the sustaining member 17 to carry it out of engagement with the teeth on the rod 18, the shifting of the carriage 23 to locate the left-hand jaw 10 in desired position, and the operation of the sustaining member 17 to carry it back into engagement with the teeth on the rod 18, are all effected by means of a horizontally disposed operating rod 24 having a pair of scales 26 (only one being shown) on the right-hand end thereof graduated in half-ems which cooperate with a pointer 25 carried by the vise frame to give a visible indication of the position at which the left-hand jaw 10 is set. For further details of the mechanism so employed for setting the left-hand jaw 10, reference may be made to U. S. Patent No. 1,839,241 granted to J. G. McNamara, January 5, 1932.

At a point between the bearings 20, 21, and immediately adjacent the right-hand bearing 21, the rod 18 is provided with a collar 27 keyed thereto by a pin 28 and abutting against a vertical reciprocating wedge 29. In rising, the wedge 29 is adapted to move the rod 18 slightly to the right against the action of a spring 30 seated in a recess formed in the bearing 21, so as to position the jaw 10 exactly to measure preparatory to the expansion of the line between the jaws 10

and 11, and, in descending, the wedge 29 allows the spring 30 to retract the rod 18 a similar distance in order that the line may be lifted readily from between the jaws 10 and 11 for distribution after the casting operation.

Ordinarily the wedge 29 is supported facewise by an anti-wear shoe 32 which banks against the inner end of an adjustable bushing threaded through the left-hand bearing 20 and clamped in place by means of a clamping screw 33, the bushing being so positioned that when the anti-wear shoe 32 banks against the inner end thereof slugs may be cast to standard measures in ems or half-ems. Occasionally, however, bastard slug measures are desired which require an auxiliary adjustment of the left-hand jaw 10 in fractions other than a half-em, and this is ordinarily accomplished by loosening the clamping screw 33 turning the bushing to adjust the inner end thereof the slight extent desired, and then re-tightening the clamping screw.

In accordance with the present invention, however, means are provided for making auxiliary adjustments of the left-hand jaw 10 without disturbing the clamping screw 33, and to this end the usual bushing in the left-hand bearing 20 is replaced with a main bushing 34 having an auxiliary bushing 38 adjustably mounted therein.

In the preferred embodiment of the invention illustrated in Figs. 1 to 5 inclusive, the end of the toothed rod 18 is passed through the bushing 38 and the latter threaded through the main bushing 34 which, in turn, is threaded through the usual left-hand split bearing 20. The outer end of the main bushing 34 is provided with a turning collar 36 recessed circumferentially to produce a hub portion 37. During assembly, the main bushing 34 is threaded through the bearing 20 until the inner end thereof is so positioned that, when the anti-wear shoe 32 banks thereagainst, slugs will be cast to standard measures in ems or half-ems, after which it is clamped in fixed position by means of the clamping screw 33.

The auxiliary bushing 38 is longer than the main bushing 34 and at its outer end is formed with an annular flange 39 having a recess 40 to receive the hub portion 37 on the turning collar 36, the latter providing a fixed face 41 and the recess an oppositely disposed face 42 which may be carried into and out of contact with the fixed face simply by turning the auxiliary bushing 38. When the oppositely disposed faces 41 and 42 are brought into contact, the inner end of the auxiliary bushing 38 protrudes exactly six points beyond the inner end of the main bushing 34, and the pitch of the screw threads is such that the auxiliary bushing 38 travels slightly more than this distance during one complete rotation thereof. A ring 43 is positioned about the turning collar 39 on the auxiliary bushing 38, and it is provided with a tapped hole to receive the threaded end 44 of a turning pin 45 by means of which the ring 43 may be locked to the collar 39 in a desired position. A set of five washers, designated 46 to 50 in Fig. 8, varying in thickness from one point up to and including five points, is provided for use in connection with this embodiment of the invention, and they are adapted to be placed about the auxiliary bushing 38 and within the recess 40.

When it is desired to cast slugs to standard measures, in ems or half-ems, the auxiliary bushing 38 is so positioned in the main bushing 34 that the inner end thereof is just short of the inner end of the main bushing, which position is

determined by the banking of the turning pin 45 against a stop pin 51 carried by the bracket 22 (see Figs. 4 and 5). The left-hand jaw 10 may then be adjusted along the toothed rod 18 until the distance between the jaws 10, 11, accord with the length of the standard measure slug it is desired to cast. Under these conditions, when the wedge 29 rises prior to line justification, the anti-wear shoe 32 banks against the inner end of the main bushing 34 and so forces the rod 18 and the left-hand jaw 10 to the right the desired distance in the customary way.

When, however, it is desired to reduce the length of the line, say, one point from the measure for which the left-hand jaw is set, the 5 pt. washer 50 is placed in the recess 40 and the auxiliary bushing 38 is then threaded inwardly through the main bushing 34 until the washer is clamped between the oppositely disposed faces 41 and 42, at which time the inner end of the auxiliary bushing protrudes one point beyond the inner end of the main bushing 34. Under these conditions, when the wedge 29 rises, since the anti-wear shoe 32 banks against the inner end of the auxiliary bushing 38, the toothed rod 18 and left-hand jaw 10 will be set one point farther to the right than when the shoe banks against the inner end of the main bushing 34.

In like manner when it is desired to cast slugs reduced in length two points, three points, four points, or five points under the measure for which the left-hand jaw 10 is set, 5 pt. washer 50 is replaced with a 4 pt. washer 49, a 3 pt. washer 48, a 2 pt. washer 47, or a 1 pt. washer 46, as the case may be. In making these changes, the ring 43 is reset each time so that when the auxiliary bushing 38 is turned to retract it, the inner end thereof is certain to be carried back within the inner end of the main bushing 34 when further rotation thereof is prevented by the engagement of the turning pin 45 with the stop pin 51.

It will be understood that in this preferred embodiment, by selecting the appropriate washer 46, 47, 48, 49 or 50, the machine may be adapted to cast slugs to whatever bastard measure may be desired. Normally the parts will be set in the position shown in Figs. 4 and 5, with the turning pin 45 banking against the stop pin 51, this being the position of the parts when slugs are to be cast to standard measures in ems or half-ems. Then in casting slugs to the bastard measure as determined by the selected washer, the turning pin 45 is moved away from the stop pin 51 until the rotation of the auxiliary bushing 38 is arrested by the selected washer as the latter is clamped between the opposed faces 41 and 42 on the main and auxiliary bushings respectively. In resetting the machine for standard measure slugs, the turning pin 45 is restored to its original position in engagement with the stop pin 51, with drawing the auxiliary bushing out of contacting relation to the wedge shoe 32 and causing it to bank against the main bushing 34.

In the second embodiment illustrated in Figs. 6 to 9 inclusive, the auxiliary bushing 55 is slightly mounted in a fixed main bushing 56. The outer end of the main bushing 56 terminates in an annular flange 57 having seven detent pockets or recesses 58 formed in the outer face thereof. These detent pockets 58 are spaced forty-five degrees apart around the face of the flange 57 except for two adjacent ones (those for the dial settings of 0 and 1) which are spaced ninety degrees apart. The auxiliary bushing 55 is longer than the main bushing 56, and it is provided with

a stud 60 which projects into a slot 61 cut in the main bushing, so that the auxiliary bushing may be displaced longitudinally but not rotated with respect to the main bushing. A recessed annular turning member 62, having an offset bearing portion 63 and a retaining collar 64, is mounted on the outer end of the main bushing 56 with the bearing portion 63 journaled on the outer periphery of the annular flange 57 and the retaining collar 64 engaging immediately behind the said flange. A nut 65 is threaded into the recessed portion of the turning member 62 and onto the outer end of the auxiliary bushing 55, the arrangement being such that the nut 65 and the turning member 62 may be rotated as a unit about the main bushing 56 and so cause longitudinal displacement of the auxiliary bushing 55. The pitch of the threads on the auxiliary bushing 55 is such that for each forty-five degree rotation of the turning member 62 and the nut 65 about the main bushing 56, the auxiliary bushing 55 is displaced inwardly or outwardly through the main bushing 56 a distance equal to one point. To aid the assembly of parts, the annular nut 65 is provided with a pair of oppositely disposed holes 66 on the outer face thereof to receive the ends of a spanner wrench. In addition, the annular nut 65 is provided with a drilled hole 67 in which is positioned a ball detent 68 to cooperate with the pockets 58 formed on the main bushing 56, a spring 69 urging the ball 68 inwardly against the face of the annular flange 57 and maintaining it under compression by a set screw 70 threaded into the outer end of the hole. The hole 67 is so positioned in the annular nut 65 that when the inner end of the auxiliary bushing 55 is one point to the left or behind the inner end of the main bushing 56, the spring-pressed ball detent 68 is seated in that pocket 58 which corresponds to the zero setting of the dial. A dial ring 71 is positioned about the recessed turning member 62 and it is provided with seven indicating marks reading from 0 to 6 and spaced forty-five degrees apart except for the marks 0 and 1 which are spaced ninety degrees apart. The dial ring 71 is secured to the turning member by means of a set screw 72, and during assembly the ring is positioned with the zero mark opposite a pointer 73 carried by the bracket 22.

In this second embodiment, when it is desired to cast slugs to standard measures in ems or half ems, the anti-wear shoe 32 banks against the inner end of the main bushing 56 in the usual manner when the wedge 29 rises prior to line justification. In the event, however, that it is desired to cast slugs to a bastard measure, say one point less than the measure for which the jaws 10, 11, are set, the turning member 62 is rotated counter-clockwise through ninety degrees to carry the spring-pressed ball detent 68 from the pocket 58 which corresponds to "0" on the dial ring 71 to the detent pocket which corresponds to "1" on the dial ring, and since for each forty-five degree rotation of the turning member the auxiliary bushing 55 is displaced one point, the inner end thereof will be set one point beyond the inner end of the main bushing 56. Under these conditions, when the wedge 29 rises prior to the justification of the line, the anti-wear shoe 32, which engages the inner end of the auxiliary bushing 55, will set the toothed rod 18 and the left-hand vise jaw 10 one point to the right beyond their normal position. In like manner, when it is desired to shorten the line two points, three points, four points, five points, or six points,

the turning member 62 is rotated counter-clockwise through an additional forty-five degrees, an additional ninety degrees, an additional one hundred thirty-five degrees, an additional one hundred eighty degrees, or an additional two hundred twenty-five degrees, as indicated by the marks 2, 3, 4, 5 or 6 on the dial ring 71 being brought into register with the pointer 73, to set the inner end of the auxiliary bushing 55 corresponding distances beyond the inner end of the main bushing 56. In the drawings the member 62 is shown in its extreme position of adjustment with the dial marking "6" in register with the pointer. The spring-pressed ball detent 68, by engaging in the appropriate pocket 58, will lock the auxiliary bushing 55 in its various adjusted positions.

After the machine has been set for casting slugs to a bastard measure and it is desired to reset it for casting slugs of standard measure, the turning member 62 is rotated in a clockwise direction to bring "0" on the dial ring 71 back into register with the pointer 73. To insure this reverse rotation of the dial ring in resetting the machine for standard measure slugs, the dial ring 71 may be provided with a stop pin 71^a to engage the pointer 73 in the extreme position of adjustment of the auxiliary bushing, as when the mark "6" on the dial ring registers with the pointer 73, thus preventing the operator from turning the dial ring in a counter-clockwise direction from "6" to "0".

In a third embodiment illustrated in Figs. 10 to 13 inclusive, the auxiliary bushing 75 is threaded through the main fixed bushing 76 and is provided at its outer end with a turning disk 77 which is secured thereto by means of a set screw 78. On its outer periphery, the turning disk 77 bears dial marks reading from 0 to 6 and these dial marks are spaced forty-five degrees apart, with the exception of the marks 0 and 1 which (as in the second embodiment) are spaced ninety degrees apart. A plate 79 is clamped between the outer end of the threaded portion of the auxiliary bushing 75 and the inner face of the turning disk 77, and the lower end thereof is slidably mounted on a stud 85 threaded into the outer end of a second stud 86 carried by the bracket 22, the arrangement being such that when the disk 77 is turned to move the auxiliary bushing 75 inwardly or outwardly through the main bushing 76 the plate 79 slides back and forth on the stud 85 but does not turn. On its outer face, the plate 79 is provided with seven detent pockets or recesses 80 spaced apart in accordance with the dial markings on the turning disk 77, and the latter is provided with a drilled hole 81 in which is positioned a ball detent 82 to cooperate with the detent pockets 80 and actuated by a spring 83 reacting against a set screw 84 threaded into the outer end of the drilled hole. The pitch of the teeth on the bushings 75 and 76 is such that the auxiliary bushing 75 is displaced exactly one point with respect to the main bushing 76 during each forty-five degree rotation of the turning disk 77.

In assembly, the disk 77 is positioned with the dial mark "0" in register with a horizontal shoulder 87 formed on the plate 79 and constituting a pointer. The spring-pressed ball detent 82 is then seated in that pocket 80 from which it is necessary to rotate the disk clockwise through ninety degrees to carry the detent to the next pocket, and the inner end of the auxiliary bush-

ing 75 is positioned one point behind or to the left of the inner end of the main bushing 76. Under these normal conditions, the slugs will be cast to standard measures in ems or half-ems, the anti-wear shoe 32 banking against the inner end of the main fixed bushing 76 in the usual manner when the wedge 29 rises prior to the line justification. When, however, it is desired to cast slugs to bastard measure, say one point less than the measure for which the jaws have been set, the disk 77 is rotated clockwise through ninety degrees to register its dial marking "1" with the pointed 87, and since for each forty-five degree rotation of the disk the auxiliary bushing 75 is displaced one point, the inner end thereof is moved inwardly until it protrudes one point beyond the inner end of the main bushing 76, which will result in setting the toothed rod 18 and the left-hand jaw 10 one point to the right beyond their normal position. In like manner when it is desired to cast slugs two, three, four, five, or even six points less than the measure for which the jaws 10, 11, have been set, the disk 77 is turned through an additional forty-five degrees, an additional ninety degrees, an additional one hundred thirty-five degrees, an additional one hundred eighty degrees, or an additional two hundred twenty-five degrees, as indicated by the dial markings 2, 3, 4, 5 and 6 being brought into register with the pointer 87, to set the inner end of the auxiliary bushing 75 corresponding distances beyond the inner end of the main bushing 76, the spring-pressed ball detent 82 acting automatically to lock the auxiliary bushing in its various adjusted positions. The disk 77 may be provided with a stop pin 88 to engage the pointer 87 in its extreme position of adjustment as indicated by the dial marking "6", thus compelling the operator to turn the disk in a counterclockwise direction in restoring the dial marking "0" in register with the pointer when the machine is to be reset for casting standard measure slugs.

Having thus described our invention, what we claim is:

1. In a slug casting machine, the combination of an adjustable jaw, a relatively fixed jaw, a toothed rod to which said adjustable jaw may be locked in different positions with respect to said fixed jaw for slug measures of ems and half-ems, means for locating said rod in one position when it is desired to cast slugs of such coarser measures, and auxiliary means for locating said rod in other positions when it is desired to cast slugs of finer measures.

2. In a slug casting machine, the combination of an adjustable jaw, a relatively fixed jaw, a toothed rod to which said adjustable jaw may be locked in different positions with respect to said fixed jaw for slug measures of ems and half-ems, means for locating said rod in one position when it is desired to cast slugs of such coarser measures, and auxiliary means for locating said rod in other positions when it is desired to cast slugs point fractions short of the em or half-em measure for which the jaws are set.

3. In a slug casting machine, the combination of an adjustable jaw, a relatively fixed jaw, a toothed rod to locate said adjustable rod in different positions, and means for adjusting the rod endwise to different positions for slug measures of ems or half-ems and fractions less than a half-em, said means including a bearing

for said rod having a pair of bushings, one being adjustable relatively to the other.

4. In a slug casting machine, the combination of an adjustable jaw, a relatively fixed jaw, a toothed rod, a bearing having a fixed main bushing and an adjustable auxiliary bushing in which one end of said rod is fitted, means including said fixed main bushing for locating the rod endwise in one position for slug measures of ems or half-ems, and means including said adjustable auxiliary bushing for locating said rod endwise in other positions for slug measures in fractions of less than a half-em.

5. In a slug casting machine, the combination of an adjustable jaw, a relatively fixed jaw, a toothed rod, means for locking said adjustable jaw to said rod in positions which differ in half-ems with respect to said fixed jaw, a bearing for said rod, means for imparting limited endwise movement to said rod with respect to said bearing, a fixed main bushing carried by said bearing and adapted to so locate said rod before the endwise movement thereof that the em or half-em measure for which the jaws are set is obtained, and an adjustable auxiliary bushing carried by said bearing and adapted to so locate said rod before the endwise movement thereof that the em or half-em measure for which the jaws are set is changed a desired fraction of less than a half-em.

6. In a slug casting machine, the combination of an adjustable jaw, a relatively fixed jaw, a toothed rod, means for locking said adjustable jaw to said rod in positions which differ in half-ems with respect to said fixed jaw, a bearing for said rod, means for imparting limited endwise movement to said rod with respect to said bearing, a main bushing fixed in said bearing and adapted to so locate said rod before the endwise movement thereof that the em or half-em measure for which the jaws are set is obtained, and an adjustable auxiliary bushing mounted in said fixed main bushing and adapted to so locate said rod before the endwise movement thereof that the em or half-em measure for which the jaws are set is changed a desired fraction of less than a half-em.

7. In a slug casting machine, the combination of an adjustable jaw, a relatively fixed jaw, a toothed rod, means for locking said adjustable jaw to said rod in positions which differ in half-ems with respect to said fixed jaw, a bearing for said rod, means for imparting limited endwise movement to said rod, a fixed main bushing in said bearing and adapted to so locate said rod before the endwise movement thereof that the em or half-em measure for which the jaws are set is obtained, an adjustable auxiliary bushing mounted in said fixed bushing and adapted to change the location of said rod before the endwise movement thereof, and means for so adjusting said auxiliary bushing in said fixed bushing that the position of said rod is changed a desired fraction of less than a half-em before the endwise movement thereof.

8. In a slug casting machine, the combination of an adjustable jaw, a relatively fixed jaw, a toothed rod, means for locking said adjustable jaw to said rod in positions which differ in half-ems with respect to said fixed jaw, a bearing for said rod, means for imparting limited endwise movement to said rod, a fixed main bushing in said bearing and adapted to so locate said rod before the endwise movement thereof that the em or half-em measure for which the jaws are

set is obtained, an adjustable auxiliary bushing mounted in said fixed bushing and adapted to change the location of said rod before the endwise movement thereof, means for so adjusting the auxiliary bushing in said fixed bushing that the position of said rod is changed a desired fraction of less than a half-em before the endwise movement thereof, and means for locking said auxiliary bushing in adjusted position.

9. In a slug casting machine, the combination of an adjustable jaw, a relatively fixed jaw, a toothed rod, means for locking said adjustable jaw to said rod in positions which differ in half-ems with respect to said fixed jaw, a bearing for said rod, means for imparting limited endwise movement to said rod, a fixed main bushing in said bearing and adapted to so locate said rod before the endwise movement thereof that the em or half-em measure for which the jaws are set is obtained, an adjustable auxiliary bushing mounted in said fixed bushing and adapted to change the location of said rod before the endwise movement thereof, means for so adjusting the auxiliary bushing in said fixed main bushing that the position of said rod is changed a desired fraction of less than a half-em before the endwise movement thereof, means for locking said auxiliary bushing in adjusted position, and means for indicating the position in which said auxiliary bushing is locked.

10. In a slug casting machine, the combination of an adjustable jaw, a relatively fixed jaw, a toothed rod to locate said jaw in different positions with respect to said fixed jaw, a bearing for said rod, a fixed main bushing threaded in said bearing and adapted to locate said rod in one position for slug measures of ems or half-ems, and an adjustable auxiliary bushing threaded in said main bushing and adapted to locate said rod in other positions for slug measures in fractions of less than a half-em.

11. A combination according to claim 10, wherein in the adjusted position of the auxiliary bushing is determined by a washer inserted between it and the main bushing.

12. A combination according to claim 10, wherein the adjusted position of the auxiliary bushing is determined by a washer inserted between it and the main bushing, said washer being one of a set of varying dimensions and replaceable at will by any other washer of the set.

13. A combination according to claim 10, wherein the auxiliary bushing is provided with a dial graduated for point adjustments of the toothed rod.

14. A combination according to claim 10, wherein the auxiliary bushing is provided with a dial graduated for point adjustments of the toothed rod, and wherein the dial markings 0 and 1 are more widely spaced apart than the remaining dial markings, for the purpose described.

15. A combination according to claim 10, wherein the auxiliary bushing may be located in one or another of a series of adjusted positions according to the point dimensions of the slug measures desired.

16. A combination according to claim 10, wherein the auxiliary bushing is provided with a dial graduated for point adjustments of the toothed rod and with a locking detent to hold said bushing in one or another of its adjusted positions.
